ALBERT R. J. DEARDEN, OF JERSEY CITY, NEW JERSEY.

HEATER.

Application filed April 21, 1920, Serial No. 375,561. Renewed February 17, 1922. Serial No. 537,358.

To all whom it may concern:

Be it known that I, ALBERT R. J. DEARDEN, a citizen of the United States, and a resident of Jersey City, in the county of Hudson and State of New Jersey, have invented a new and Improved Heater, of which the following is a description.

My invention relates to a heater and more particularly to a heater in the form of a radiator and having heating means.

The general object of the invention is to embody in a heater of the indicated character, a novel arrangement of flues forming a circulation circuit in coaction with the heat-producing means with a view to the effective application, utilization and radiation of the generated heat.

A more specific object of the invention is to produce a practical embodiment of the invention reflecting important practical considerations with respect to simplicity of construction and facility of assemblage, adjustment and repair.

The above and other objects as will appear are attained by a heater possessing the distinctive features and combinations of parts as hereinafter particularly described and defined in the claims.

Reference is to be had to the accompanying drawings forming a part of this specification, it being understood that the drawings are merely illustrative of one example of the invention.

Figure 1 is a longitudinal vertical section of a heater embodying my invention;

Figure 2 is a transverse vertical section on the line 2—2, Figure 1;

Figure 3 is a transverse vertical section on the line 3—3, Figure 1.

Figure 4 is a view showing a valve-controlled vent in elevation.

In carrying out my invention in accordance with the illustrated example, the heater is made to embody a series of vertically disposed radiator sections 10. These may be formed in any suitable manner and in practice the sections are separately cast or formed of sheet metal. Each of the sections, or at least the central section, may be made up of corresponding halves, the making of the central section in halves being with a view to the assembling of the burner and the nozzle associated therewith as hereinafter referred to. Said sections are assembled side

by side and held together by suitable means such as longitudinal tie rods 11, 12.

One radiator section is arranged to constitute an uptake flue for the air products of combustion and forms part of the circulating circuit including a downtake flue or flues and cross connections between the same and the uptake flue. Advantageously, the uptake flue designated 10^a, is central, there being a series of downtake flues 10^b at each side thereof. The communicating openings 10^c are provided in the radiator sections at the top of the flues to constitute in effect a transverse flue establishing communication between the downtake flues at their upper ends and the uptake flues. Suitable means is arranged to deflect the ascending air and gases laterally from the uptake flue, 10^a, to the downtake flues, 10^b. Said deflecting means in its preferred form consists of an arched element 13 disposed transversely in the central radiator section and presenting opposite side surfaces curved over laterally toward the transverse flue 10^c.

For completing the lower portion of the circulating circuit the arrangement will vary with the character and form of the heat-producing means.

In the illustrated example a burner for fluid fuel is employed and the lower lateral radiator sections at their lower portions are adapted to said burner and its appurtenances. The burner may, as shown, take the form of a transverse jet tube 14 disposed at the bottom of the uptake flue 10^a transversely thereof. Over the burner 14 I provide a nozzle 15 disposed transversely in the flue 10^a, the walls of said nozzle being convergent above the jet tube 14. One end 16 of nozzle 15 is open and extends through a side of the radiator section 10 to afford access to the jet tube 14 for lighting the burner, the open end having a suitable movable closure 17. The burner being of the Bunsen type, the gas connection 18 therefor is conveniently arranged near the open end 16 of nozzle 15 as well as air inlet opening 19, the jet tube presenting interiorly an approximately vertical surface 20 against which the incoming air and gas currents impinge for mixing.

Lateral openings 10^d are formed in the several sections 10 and constitute in effect a transverse return flue establishing communication between the downtake flues 10^b and

the uptake flue 10^a and with a burner and nozzle employed as described the nozzle will terminate at the openings 10^d so that the nozzle discharges to the uptake flue 10^a adjacent to the openings 10^d at each side of the nozzle. The walls defining the openings 10^d are flaring so that the opposed walls at opposite sides of the nozzle 15 converge upwardly as viewed in vertical section through the walls, the result being that the walls of the openings at the top and the nozzle tip constitute in effect injector elements to assist in drawing the air laterally through the flue represented by the openings 10^d to the uptake flue 10^a.

In addition to the transverse return flue constituted by the openings 10^d, I produce a lower series of communicating transverse openings 10^e in the radiator sections constituting in effect a second return flue between the downtakes 10^b and the uptake 10^a and the jet tube 14 is disposed in the plane of said openings 10^e to draw air toward the burner and afford an ample supply of oxygen to sustain combustion. The lowermost transverse flue constituted by the openings 10^e, it will thus be understood, functions more particularly in connection with the fluid fuel burner.

With the above described construction, the heat-producing means being in action an active upflow will take place in flue 10^a and the current will be deflected laterally by the deflector 13 in opposite directions into the upper transverse flue produced by the openings 10^e from which transverse flue the air and gas currents will be drawn downwardly through the downtakes 10^b under the suction induced in the transverse flues represented by the openings 10^d, 10^e due to the influence of the injector action at the top of the nozzle 15 and the action of the burner tube 14.

The arrangement of the circulating flues, as described, lends itself to the disposing of one transverse tie rod 11 to pass through the upper transverse flue produced by openings 10^e and the other tie rod 12 in the lowermost transverse flue represented by the openings 10^d. The ends of rod 11 extend through the outer sections 10 and said sections have vent openings 21 optionally controllable by turnable dampers 22. Similarly, the lower rod 12 in flue 10^d extends through the end radiator sections 10.

At the ends of the transverse flue represented by the openings 10^d, said flue is open to the atmosphere through the medium of series of small openings 23, 24, one series above the other, permitting ingress of air or egress of air and hot products, the upper and lower series of openings permitting egress through the upper series simultaneously with ingress of air through the lower series or ingress or egress through both series according to the heat and pressure conditions,

The height, that is to say, the effective length of the downtake flues 10^b, will in practice not exceed the critical point of induced down draft effective under the suction produced in the transverse flue represented by the openings 10^d (plus the suction in flue represented by the openings 10^e), and as the effective down draft influence has its limitations, the radiator may advantageously be made of a height independent of these limitations, to the end that an ample radiating surface is produced. The radiator sections 10, may, as shown, be made to rise a substantial distance above the upper transverse flue produced by openings 10^e to thereby present above said flue and communicating therewith, vertical pockets 10^f within the respective sections 10, said pockets factoring in inducing circulation within the radiator as will appear.

The several radiator sections may embody a feature known in radiator construction, to wit; vertical slots 25 in the sections at each side of the openings 10^e, 10^d. These can be made to terminate at the top at such a point that the heated currents passing transversely through the openings 10^e can rise in the different radiator sections to take a downward course and not be confined to passing through the downtake flues 10^b to the central space between the walls 26 of the slots 25. In any event the suction produced in the lower flue represented by the openings 10^d will be effective in producing a downward suction in the spaces of a downtake flue 10^b at the outer sides of the walls 26, thus causing more or less of the hot air and products to rise at the flue represented by the openings 10^e and pass over the walls 26 and downwardly. At the same time, there is an effective down draft induced in the central space between the pair of slots 25 and directly downwardly from the openings 10^e to the openings 10^d in addition to the circulation outside of the slots 25 and their walls 26.

The down flow through the outer vertical spaces in the radiator section (outside of the slots 25 and their walls 26) due to the suction induced by the lower flue formed by the openings 10^d, is in practice also assisted by the fact that the heat in the central space between the two slots 25 and walls 26 is much more intense than in the outer spaces so that in effect there is a counteracting expansion of the air in the central space simultaneously with a cooling contraction of the air in the outer spaces, the currents being given, in this manner, a tendency to pass downwardly in the outer spaces as well as in the central spaces where the suction is more directly effective.

At the ends of the rods 12 simple riveting will suffice but I prefer to employ cup-shaped washers 27 beneath the heads to simulate

the dampers or valves 22. I would mention here also, that in practice I may form air inlet holes 28 in the central radiator section adjacent to the burner or other source 5 of heat. The numeral 29 indicates opposed projections on the respective sections, the projections of a pair being in position to engage each other and brace the sections when assembled as known in radiator construction.

10 Reverting to the slots 25 and the spaces or columns into which the radiator sections are thus divided, it will be understood that the number of slots in the respective sections may vary and indeed the provision 15 of any slots is not necessary to the invention in all its phases. The slots, however, are preferred since in addition to increasing the radiating surface they are utilized for an important function, as follows: It will be 20 observed from Figure 3 that the slots 25 are omitted from the central sections, the uptake 10^a having unslotted walls, which are highly heated and cause the air to rise at both sides of the central section between the same 25 and the adjacent sections, which are spaced by the walls of the openings 10^c, 10^d, 10^e. The result of the highly heated central section is that the air will be drawn through 30 the several slots 25 toward the central section and will rise adjacent to the latter, thereby circulating the air. Thus, the heating is by conduction, distributing the heat throughout the sections; by convection due to the circulation of the air through the slots 35 25 inwardly to the central section, and upwardly at the sides of the latter; and by radiation of the heat from the various sections.

I would state in conclusion that while the 40 illustrated example constitutes a practical embodiment of my invention, I do not limit myself strictly to the mechanical details herein illustrated, since manifestly the same can be considerably varied without departure from the spirit of the invention as defined in the appended claims.

Having thus described my invention, I claim:—

1. A heater including radiator sections, 50 one of which constitutes an uptake flue and others downtake flues, there being a transverse flue establishing communication between the upper ends of said downtake flues and said uptake flue, and a second trans- 55 verse flue forming a return connection between said downtake flues and said uptake flue below the first-mentioned transverse flue, to form a circulating circuit; and heating means in said uptake flue adjacent to its 60 lower end, below said return transverse flue; together with a nozzle over the heating means and terminating adjacent to the top of the return transverse flue, the upper end of said nozzle and the said return transverse 65 flue jointly presenting members forming an

injector to induce a current in said uptake flue.

2. A heater including a series of radiator sections, an approximately central one of which constitutes an uptake flue, there being 70 sections at each side of the central section constituting downtake flues, there being a transverse flue transecting said uptake flue and establishing communication between the same and the upper ends of the several 75 downtake flues at each side of the uptake flue, as well as a return transverse flue below the first-mentioned transverse flue, and another return transverse flue below the second mentioned flue; together with heating means in 80 the uptake flue between said two return flues.

3. A heater including a series of radiator sections, an approximately central one of which constitutes an uptake flue, there being 85 sections at each side of the central section constituting downtake flues, there being a transverse flue transecting said uptake flue and establishing communication between the same and the upper ends of the several 90 downtake flues at each side of the uptake flue, as well as a return transverse flue below the first-mentioned transverse flue, and another return transverse flue below the second mentioned flue; together with heating 95 means in the uptake flue between said two return flues, said heating means including a burner and a nozzle over said burner, and terminating adjacent to the juncture of said uptake flue and the first-mentioned return flue.

4. A heater including a series of radiator sections, one of which constitutes an uptake flue and others, downtake flues, there being a transverse flue establishing communication 105 between the uptake flue and the several 105 downtake flues as well as a second transverse flue below the first-mentioned transverse flue and establishing a return connection between the several downtake flues and the uptake flue and a third transverse flue 110 below the second transverse flue and forming a second return flue; together with a source of heat for the uptake flue between the two transverse return flues, said radiator sections presenting vertical pockets above 115 the first-mentioned transverse flue and above the downtake flues, and continuous with the latter to communicate therewith and with said first-mentioned transverse flue.

5. A heater including upstanding radiator 120 sections, one of which constitutes an uptake flue and others downtake flues, there being upper and lower transverse flues connecting the uptake flue with the downtake flues, a source of heat in said uptake flue and vertical partition elements dividing said 125 downtake flues each into an inner flue passage and outer flue passages at the sides of the inner flue passage, said transverse flues communicating with the downtake flues at the inner 130

passages thereof, said partitions rising above the upper transverse flue and terminating below at the lower transverse flue; together with means to induce an upward current in 5 said uptake flue.

6. A heater including a series of upstanding radiator sections one of which constitutes an uptake flue and others at each side of the uptake flue constituting downtake 10 flues, there being upper and lower transverse flues transecting the uptake flues and the several downtake flues, establishing a 15 circulating circuit, a deflector at the junction of the uptake flue and the upper transverse flue to direct into the latter in opposite directions the currents ascending in the uptake flue, said deflector being of arched form and disposed in said uptake flue in a plane 20 approximately at right angles to a line drawn horizontally through the several radiator sections, the upper portion of said deflector lying adjacent to the upper transverse flue and the side surfaces of said deflector curving laterally in opposite 25 directions from the medial plane of the uptake flue toward said transverse flue, said curved side surfaces following the arched lines of the deflector, the lower ends of the arched deflector lying in the uptake flue below the upper 30 transverse flue to cause the currents to concentrate toward the top of the deflector at the plane of the upper transverse flue and deflect the currents laterally into the said upper flue.

35 7. A heater including a series of upstand-

ing radiator sections one of which constitutes an uptake flue, and others at each side of the uptake flue constituting downtake flues, there being an upper transverse flue transecting the uptake flue and the several 40 downtake flues establishing communication therebetween, an arched deflector at the junction of the uptake flue and said transverse flue to direct into the latter in opposite directions the currents ascending in the uptake flue, there being a transverse return flue 45 connection between the several downtake flues and the uptake flue below the first mentioned transverse flue; together with heating means in the uptake flue adjacent to the 50 lower transverse flue.

8. A heater including a series of upstanding radiator sections one of which constitutes an uptake flue and others at each side of the uptake flue constituting downtake 55 flues, there being an upper transverse flue transecting the uptake flue and the several downtake flues establishing communication therebetween, a deflector forming an arched closure of the uptake flue at the plane of the 60 upper transverse flue to direct into the latter in opposite directions, the currents ascending in the uptake flue, there being a transverse return flue connection between the several 65 downtake flues and the uptake flue below the first-mentioned transverse flue; together with heating means in the uptake flue adjacent to the lower transverse flue.

ALBERT R. J. DEARDEN.
